UNITED STATES PATENT OFFICE.

DAVID E. COOL, OF ST. LOUIS, MISSOURI, ASSIGNOR, BY MESNE ASSIGNMENTS, TO NORWAY WELT PATENTS TRUST, A TRUST ESTATE.

MACHINE FOR OPERATING ON SOLES.

Application filed March 25, 1921. Serial No. 455,507.

This invention relates to machines for operating on soles and more particularly for providing the margin of a sole, such as an insole, with an edge adapted to permit attachment thereto of the upper.

In a certain type of shoe, the insole is provided with a wing and with an overhanging shoulder inside and above the wing to permit attachment thereto of the upper.

One of the objects of this invention, therefore, is to provide a machine for operating on soles, having provisions for slitting the sole edge therealong and for cutting the sole face along but inside of the sole margin so as to provide a wing with a shoulder above and inside of the wing.

Another object is to provide a machine of the character described in which the operation of the cutting means is effective and efficient.

Further objects will appear from the detail description taken in connection with the accompanying drawing, in which:

Figure 1 is a side elevation of a machine illustrating an embodiment of this invention;

Figure 2 is an enlarged section on the line 2—2, Figure 1;

Figure 3 is a perspective of the tool;

Figure 4 is an elevation; and

Figure 5 is a section through an insole as formed in the machine.

Referring to the accompanying drawing, and more particularly to Figure 5, the insole 1, as shown, has a wing 2 thereon with an overhanging shoulder 3 arranged above but inside of the wing. This sole is formed by slitting the sole edge therealong on the line 4, thereby forming a lip 5 and by severing 40 the lip by a cut taken along but inside of the sole margin and at an acute angle so as to form an overhanging shoulder 3.

The sole is formed by a tool 6 as shown in Figure 3, which, in the particular embodiment of this invention, is a stationary tool which can be placed on any suitable channeling machine as shown in Figure 1. The tool has a slitting edge 7 forming a slitting knife which inclines upwardly towards the back so as to provide for strength, and further has a cutting edge 8 forming a sole face cutter which also thickens towards the back, and which is formed on a shank 9 provided with a slot 10 so that the sole face cutter can be clamped to the slitting cutter

by a screw 11 threaded into the body of the tool 6. The sole face cutter 8 intersects but is arranged at an acute angle to the slitting knife 7 and the cutting edge of the slitting knife is arranged in advance of the cutting edge of the sole face cutter. Either or both of the slitting knife and the sole face cutter can, of course, be sharpened by disconnecting them and wear can be taken up by adjustment provided by the clamping screw 11.

The tool can be placed in any suitable machine, such as the well known form of channeling machine shown in Figures 1 and 2, and which comprises a base 12 having hinged thereto at 13 a frame 14 normally held towards the base 12 by a spring 15 encircling a bar 16 suspended from the frame 14 and passing through the base 12 and provided with a tension screw 17. The base is provided with a shaft 18 and a counter-shaft 19, while the frame is provided with a shaft 20, the shafts being interconnected by gears and the shaft 19 has a knurled wheel 21 while the shaft 20 has a roll 22. A gauge 23 controlled and positioned by an arm 24 is also provided. A guide 25 is further provided to guide the sole in and between the rolls 21 and 22.

The construction so far described is common in the art and further detail description thereof is unnecessary since it is the structure of the ordinary channeling machine, such as illustrated in the Stanbon Patent No. 607,140, July 12, 1898.

The frame 14 has mounted thereon the tool 6. This may be accomplished by screws 26 taking through slots 27 in the tool; the tool is thus mounted beyond the gauge 23 so as to receive the sole fed between the rolls 21 and 22.

In operation, the sole is fed between the rolls 21 and 22, the edge thereof being positioned by the gauge 23 which may be operated during the operation of the machine so as to provide for extension edges in the usual manner. These rolls will, therefore, move the sole against the tool as shown in Figure 4, thereby causing the knife 7 to slit the sole edge therealong and thereafter cause the sole face cutter 8 to cut into the sole face along but inside of the sole margin and along the inside terminus of the slit, thereby severing the lip formed by the slitting operation and forming an overhanging shoulder along but

inside of the sole margin. In view of the fact that the slitting knife operates in advance of the sole face cutter, the slitting is actually accomplished in advance of the severing of the lip; with this construction the sole will be smooth and not only will breakage of the cutting edges be prevented, but the cut is a smooth and even one as the slitting is completed before the severing of the 10 lip formed by the slitting operation and the formation of the overhanging shoulder is started.

It is obvious that various changes may be made in details of construction without departing from the spirit of this invention; it is, therefore, to be understood that this invention is not to be limited to the specific details shown and described.

Having thus described the invention what is claimed is:

1. A machine for operating on soles, comprising, a support adapted to sustain the sole and present the edge thereof, a blade adapted to slit the sole edge therealong and inwardly from its margin, and a blade arranged to intersect said slit and adapted to cut the sole face along but inside of the sole margin so as to join the slit, said slitting blade operating in advance of said cutting blade.

2. A machine for operating on soles, comprising, a support adapted to sustain the sole and present the edge thereof, a blade adapted to slit the sole edge therealong, and inwardly from its margin, and a blade arranged to intersect said slit and adapted to cut the sole face at an acute angle and along but inside of the sole margin so as to join the slit, said slitting blade operating in advance of said cutting blade.

3. A machine for operating on soles, comprising, a support adapted to sustain the sole and present the edge thereof, a blade adapted to slit the sole edge therealong, and inwardly from its margin, and a blade arranged to intersect said slit and adapted thereafter to cut the sole face at an acute angle and along but inside of the sole margin so as to join the slit.

4. A machine for operating on soles, comprising, a support adapted to sustain the sole and present the edge thereof, a blade adapted to slit the sole edge therealong and inwardly from its margin, and a blade arranged to intersect said slit and adapted to cut the sole face along but inside of the sole margin so as to join the slit, the tip of said cutting blade being directed inwardly so as to form an undercut shoulder on the sole.

5. A machine for operating on soles, com-

prising, a support adapted to sustain the sole and present the edge thereof, a blade adapted to slit the sole edge therealong and inwardly from its margin, and a blade arranged to intersect said slit and adapted to 65 cut the sole face along but inside of the sole margin so as to join the slit, the tip of said cutting blade being directed inwardly so as to form an undercut shoulder on the sole, and said tip having its cutting edge 70 rearwardly of the cutting edge of said slitting blade.

6. A machine for operating on soles, comprising, a support adapted to sustain the sole and present the edge thereof, a blade adapted to 75 slit the sole edge therealong and inwardly from its margin, and a blade arranged to intersect said slit and adapted to cut the sole face along but inside of the sole margin so as to join the slit, the tip of said cutting 80 blade being directed inwardly so as to form an undercut shoulder on the sole, and said tip being directed upwardly and rearwardly.

7. In a machine for operating on soles, a tool comprising, a body adapted for attachment, a slitting blade projecting from said body, and a cutting blade attached to said body above said slitting blade and having a tip intersecting the end of a slit formed by said slitting blade.

8. In a machine for operating on soles, a tool comprising, a body adapted for attachment, a slitting blade projecting from said body, and a cutting blade attached to and for adjustment on said body above said 95 slitting blade and having a tip intersecting the end of a slit formed by said slitting blade.

9. In a machine for operating on soles, a tool comprising, a body adapted for attachment, a slitting blade projecting from said body, and a cutting blade attached to said body above said slitting blade and having a tip intersecting the end of a slit formed by said slitting blade, with the edge of said 100 slitting blade in advance of the edge of said cutting blade.

10. In a machine for operating on soles, a tool comprising, a body adapted for attachment, a slitting blade projecting from 110 said body, and a cutting blade attached to said body above said slitting blade and having a tip directed outwardly intersecting the end of a slit formed by said slitting blade, with the edge of said slitting blade in advance of the edge of said cutting blade.

In testimony whereof I affix my signature this 30th day of September, 1920.

DAVID E. COOL.
